DESIGN FOR A RIDGE ROLL

Martin L. Hunker, Dover, Ohio, assignor to Reeves Steel and Manufacturing Company,
Dover, Ohio, a corporation of Ohio

Application November 5, 1938, Serial No. 80,890

Term of patent 7 years

To all whom it may concern:

Be it known that I, Martin L. Hunker, a citizen of the United States, residing at Dover, in the county of Tuscarawas and State of Ohio, have invented a new, original, and ornamental Design for a Ridge Roll, of which the following is a specification, reference being had to the accompanying drawing, forming part thereof.

Figure 1 is a perspective view of a ridge roll, showing my new design; and

Fig. 2, a section taken substantially on the line
2—2 of Figure 1.

I claim:

The ornamental design for a ridge roll, as shown.

MARTIN L. HUNKER.
